ARTHUR E. WEBB, OF MILWAUKEE, WISCONSIN, ASSIGNOR TO THE RIGHTWAY CORPORATION, A CORPORATION OF INDIANA

SNOW REMOVER

Application filed January 9, 1928. Serial No. 245,336.

In order to keep country highways open to traffic it is necessary, in winter, to remove the snow therefrom. While an ordinary snowfall may not result in a layer of snow more than a foot or two thick, there will always be parts of a long highway in which deep drifts occur. Therefore the snow removing means employed for clearing a highway must be capable of clearing away the deep snow found in drifts. The means usually employed comprises a tractor with a deep plow. The tractors are slow moving, so that they operate very inefficiently over the main stretches of highway on which the snow is not deep. Furthermore, they are unable to force their way through exceptionally deep drifts. The result is that a number of machines must be employed to do the work that could be accomplished by a single machine if it could travel at a comparatively high speed over the main stretches of highway and could also effectively cut its way through drifts.

The object of the present invention is to produce a simple and novel machine that will operate efficiently at all times to clear away snow regardless of its depth or the variations in depth along a highway.

A further object of the present invention is to produce a simple and novel machine that will make it possible quickly and efficiently to clear the snow from a highway and then, if desired, to scatter the banked snow at the sides so as to prevent it from drifting back upon the road bed.

A further object of the present invention is to produce a simple and novel machine in which the entire power available for moving the machine ahead as well as for collecting and removing the snow may at will be utilized solely for snow collection and removal without diversion of power for the purpose of moving the machine ahead.

Another object of the present invention is to produce a simple and novel machine for collecting snow and loading it upon trucks or other vehicles in cities or other places where it is not practicable to scatter the snow that is removed.

The various features of novelty whereby

my invention is characterized will herein-after be pointed out with particularity in the claims; but, for a full understanding of my invention and of its objects and advantages, reference may be had to the following detailed description taken in connection with the accompanying drawings, wherein:

Figure 1 is a side elevation of an apparatus arranged in accordance with the present invention and associated with a snow plow attached to the front end of a tractor or the like; Fig. 2 is a top plan view of the apparatus; Fig. 3 is a vertical longitudinal section on an enlarged scale through the vertical supporting post or pedestal for the rotary snow remover; Fig. 4 is a section taken approximately on line 4—4 of Fig. 3; Fig. 5 is a section taken approximately on line 5—5 of Fig. 3; Fig. 6 is a section taken approximately on line 6—6 of Fig. 3; Fig. 7 is a section on a still larger scale, taken approximately on line 7—7 of Fig. 4; Figs. 8, 9 and 10 are respective views of the elements of the reversing mechanism; Fig. 11 is a perspective view of the snap action actuator for the reversing mechanism; Fig. 12 is a top plan view of the apparatus, having a loading conveyor attached thereto; and Fig. 13 is a view partly in side elevation and partly in section, showing the apparatus as it appears in Fig. 12.

My invention may take a great many different forms and, depending upon the aspect in which it is viewed, it may contain any desired number of the novel features constituting the invention in its most highly developed form. For the sake of brevity, I have illustrated in the drawings only a single preferred embodiment of my invention, including a loading attachment; and the detailed description will be confined to this particular embodiment as the latter will serve to explain the various novel principles and uses. Since a snow remover must be caused to travel in some manner, I shall refer to movable supporting means as a vehicle, whether it be a plow mounted for self support, a truck or tractor, or any other suitable means.

Referring to the first eleven figures of the

drawings, 1 represents a V-type snow plow mounted on a suitable extension on the front end of a power driven vehicle 2. In advance of the plow is mounted a rotary snow remover consisting of a series of radial trough-shaped buckets 3 fixed to a central horizontal transverse shaft 4 so as to form a wheel-like structure. The buckets are tied together by means of tie rods 3^a extending between them near their outer end. If no means were provided for controlling the snow after it enters the buckets in the rotary wheel, the snow would simply be thrown off tangentially in a general rearward direction and against the plow and the front end of the machine; some of the snow probably being thrown down on the road in advance of the plow. I propose to rid the road entirely of the snow collected by the rotary remover and, therefore associate with the latter a guide or deflector that will cause the snow to leave the wheel at a predetermined point, whereby the direction of flow of the discharged snow is controlled. Consequently, the snow does not leave the wheel at every point where the centrifugal force happens to be great enough, but it must travel along with the wheel until the selected discharge point is reached and the direction of escape thereby determined. The deflector or guide is shown as taking the form of a hood 5 arranged underneath and behind the wheel. The upper end of the hood, at the rear of the wheel, is preferably in the form of or joined to a conduit 6. The conduit extends upwardly and terminates at its upper end in a swiveled spout 7 in the form of an elbow whose discharge end may be turned to cause the snow to be discharged with the wind. Assuming that the bladed wheel rotates in the counterclockwise direction in Fig. 1 while moving into a mass of snow, it will be seen that the spoke-like buckets 3 become filled with snow which is thrown out of the buckets by centrifugal force into and through the conduit and the discharge spout. The wheel must of course be revolved rapidly in order that the snow may be thrown up through the spout by centrifugal force. The result is that buckets strike the snow sharply and cause the snow to be packed in the same. In other words, the snow will be compacted as it is collected. The rotary remover or collector, with its hood or housing, is carried on a boom consisting conveniently of two parallel long pipes 8, 8 of considerable diameter having adjustably mounted on their outer ends bearings 9 for the ends of the shaft or axle 4. The hood or housing may be supported from the shaft 4 and be connected to the boom by means of braces 10. Therefore, by swinging the boom, the entire snow collecting and discharging apparatus will move bodily with it. The inner or rear end of the boom is pivotally supported on

a vertical pedestal 12, so as to be capable of swinging in the vertical direction. The pedestal is mounted so that it may rotate about a vertical axis, thus permitting the boom to swing from side to side. In other words, the snow collecting and removing means may be moved bodily up and down and from side to side. The pedestal is mounted on a suitable base 13 fixed to the front end of the vehicle. As best shown in Figs. 3 and 6, the pedestal is made hollow and has a tubular lower end 14 surrounding and rotatable about a post 15 rising from the base 13. The support for the inner end of the boom consists of two hollow trunnions 16, 16 projecting from opposite sides of the pedestal at about the middle of the latter. There is a transverse horizontal shaft 17 extending through the pedestal and coaxial with the trunnions. This shaft has on one end a sprocket wheel 18 over which runs a sprocket chain 19 that in turn passes over a sprocket wheel 20 on the rotary snow collector shaft 4, as best seen in Figs. 1 and 2. The shaft 17 has thereon a bevel gear 22 meshing with a pinion 23 on the upper end of a vertical shaft 24 extending up into the pedestal from the base 13. The shaft 24 is driven through gears 25 and 26 from a horizontal driving shaft 27 axially aligned with the propeller shaft 28 of the power vehicle and adapted to be driven therefrom as will hereinafter be explained. It will be seen that when the vertical shaft 24 is rotated it causes the rotary snow remover or collector to rotate. The boom is caused to swing from side to side through the turning of the pedestal. In the arrangement shown, I have provided mechanism for automatically oscillating the pedestal so as to cause the boom to swing back and forth from one side to the other. To this end there is arranged in the upper part of the pedestal a vertical shaft 29 driven from the horizontal shaft 17 through co-operating bevel gears 30. The upper end of the shaft 29 extends into a housing 32 fixed on the upper end of the pedestal and containing the reversing mechanism for causing the automatic oscillation of the boom. The details of this mechanism, except the tripping means, are best shown in Figs. 3 and 4. Referring to these figures, it will be seen there are in the housing 32 two parallel horizontal shafts 33 and 34. The shaft 33 has fixed thereon a bevel gear 35 meshing with a pinion 36 on the upper end of the shaft 29. There are also two spur pinions 37 and 38 fixed to the shaft 33 at some distance apart. The pinion 37 meshes with a gear wheel 39 loose on the shaft 34; whereas the pinion 38 meshes with a wide pinion 40 that in turn meshes with a gear wheel 42 similar to the wheel 39 and also loose on the shaft 34. Between the wheels 39 and 42 is the movable element 43 of a double clutch; this member being splined to

the shaft 34 so as to be capable of moving lengthwise of the latter while compelled to rotate in unison therewith. On the gears 39 and 42 are clutch elements 44 and 45 respectively, for cooperation with the movable clutch element 43. When the movable clutch element is in the position shown in Fig. 4, the shaft 33 may be rotating without producing any rotation of the shaft 34, since the gears 39 and 42 will revolve upon the shaft 34. However, if the movable clutch element is shifted toward the right, the shaft 34 will be driven in one direction through the gear 39, whereas if the movable clutch element is shifted toward the left, the shaft 34 will be driven in the opposite direction through the gear 42.

On one end of the shaft 34 is a bevel pinion 46 meshing with a bevel gear 47 on the upper end of a short vertical shaft 48 extending down through the bottom of the housing 32. On the lower end of the shaft 48 is a pinion 49 meshing with a segmental rack 50 carried by a stationary part of the supporting frame 52 rising from or connected to the rear end of the base 13. It will therefore be seen that when the shaft 34 is rotated, it causes the short vertical shaft 48 to rotate, at a slower speed. However, in rotating, the pinion 49 on the shaft 48 must run along the segmental rack, therefore swinging the housing and the pedestal to which it is connected. The direction of this swinging movement depends upon the direction of rotation of the shaft 34, so that if the direction of rotation of this shaft is reversed at predetermined points, there will be a continuous oscillatory movement of the boom from side to side. The automatic reversal of the direction of rotation of the shaft 34 is brought about by automatically shifting the movable clutch element 43. This is accomplished by means of a shifter fixed to a shaft 53 extending through the housing 32 at right angles to and above the shafts 33 and 34. One end of this shaft extends into and through a small casing 54 secured to one side of the housing 33. On the end of the shaft 53, beyond the casing, is fixed a radial arm 55 the path of movement of whose lower end is crossed by two stops 56 and 57 placed at the ends of the segmental rack 50. Whenever the arm strikes one of the stops, a further continued movement of the swinging structure as a whole, causes this arm to swing so as to turn the shaft 53. When the arm strikes one of the stops, it causes the shaft 53 to turn in one direction and, when it strikes the other stop, the shaft is caused to turn in the other direction; thus throwing the clutch first into one working position and then into the other working position. In order to insure positive action in the shifting of the clutch, I have provided the features best shown in Figures 7 to 11.

The shaft 53 is made in two sections 53 and 53a. The clutch shifting fingers 58 are fixed to the section 53a, whereas the arm 55 is fixed to the section 53. Fixed to the section 53 is a plate 59 whereas on the section 53a of the shaft is secured what may be termed a clutch tripping anvil 60 provided with two arms 62 and 63 arranged at an angle to each other and projecting toward the same side of the shaft. On that edge of the plate 59 lying on the same side of the shaft at the free ends of the arms 62 and 63 are lugs 64 and 65 spaced apart an angular distance with respect to the axis of the shaft, less than the angular distance between the arms 62 and 63. Mounted in the casing 54, parallel with the shaft 53 is a rock shaft 66 through which extend radially two loose rods 67, 67 connected at their outer ends by a transverse bar or hammer 68. Between the member 68 and the shaft 66 are springs 69, 69 each of which preferably surrounds one of the rods. The parts are so disposed and proportioned that the bar or hammer 68 engages with the edge of the plate 59 in the space between the lugs 64 and 65 and extends into the space between the arms 62 and 63 of the tripping anvil 60. The springs are always under compression, so that they tend constantly to force the bar or anvil 68 away from the rocking support for the same.

In Figure 7 the parts are shown in the positions which they occupy when the clutch is in one of its working positions, namely the bar or hammer is in engagement with the lug 64 and the arm 62. The boom, assuming that power is being applied to drive the apparatus, will now swing until the tripping arm 55 engages the stop toward which it is moving. When this occurs, the arm and the shaft section 53 will begin to turn, causing the plate 59 to swing in the clockwise direction; the lug 64 pushing the bar or hammer 68 toward the right and downwardly and compressing the springs 69. The parts are so designed that this movement will continue until the long axes of the rods 67 swing somewhat past the plane containing the long axes of the shaft 53 and the rock shaft 66. Thereupon, the springs 69 come into play to complete the swinging movement of the plate 59 and therefore the shaft section 53. It will be seen that the shaft section 53a remains stationary while the section 53 and the plate 59 are being swung by means of the tripping arm 55. However, when the hammer snaps downward, after having passed center, it strikes both the lug 65 and the arm 63, so as to swing the arm 63 and therefore the shaft section 53a in a clutch shifting direction. In other words, when the boom approaches one end of its lateral swinging movement, it sets into motion mechanism that will snap the clutch into its opposite work-

ing position and thus cause the return movement of the boom.

There is an arm 70 fixed to the outer end of the shaft section 53a whereby the clutch may be manually operated. A rod 72, as shown in Fig. 1, may extend from the arm 70 to a point within reach of the driver of the machine.

The vertical movements of the boom are produced by a suitable air hoist which, as shown in Fig. 1, comprises a cylinder 73 hung from its upper end from an arm 74 fixed to the housing 32, and a piston having the lower end of its rod 71 pivoted to a suitable bracket 75 on the boom, as indicated at 76. The weight of the boom and the parts supported thereby may be wholly or partially counterbalanced by springs 77, 77 or other suitable means. Air hoists of this kind are well known, hoists that will raise and lower and lock in any position being a common product of commerce, and need therefore not be described in detail. The pipes or tubes of which the boom is made may serve as reservoirs for air to operate the hoist; air passing from the reservoir to the hoist through a connection 78 in which there is a suitable valve 79 controlled by a rod 80 extending to a point within reach of the driver.

Air may be supplied to the reservoir, as best shown in Fig. 3, from a compressor 82 driven from the main shaft 28 through a sprocket chain drive 83 or otherwise. There may be in this drive connection a suitable clutch controlled by a handle 84, to shut off the compressor when not required. The air is delivered from the compressor through a flexible pipe 85 that divides into two branches 86 and 87, each leading to one of the pipes constituting the boom.

Between the main shaft 28 and the shaft 27 that drives the vertical shafts extending through the pedestal, there is a suitable clutch 88 controlled by a rod 89 (see Fig. 2) that actuates a clutch shifter 90.

The particular embodiment of my invention heretofore described can be operated in a variety of ways. It will be seen that the rotary removing device has cutting edges on the periphery and on both sides. Consequently, if it is pushed straight ahead into the snow, snow will enter at the periphery and at both sides. When it is swung sidewise, the effective cutting edges will be on the side that is in advance, as well as at the periphery. In other words, the removing device may be said to have inlets at the periphery and at the sides, the inlets at the periphery being the open ends of the buckets and the inlets at the sides being the spaces between the buckets. If the snow be somewhat deeper than the plow can conveniently handle, the boom may be placed and allowed to remain in a position pointing straight ahead of the plow, with the rotary snow remover positioned at any

desired height above the surface of the road. Then, when the machine is run ahead, the rotary device will cut a path down the center, while the plow clears away only the strips of snow left along the sides. In cases where the plow will successfully remove the ordinary lay of snow, the boom is swung up out of the way until a deep drift is reached. With the machine standing still, the boom is then caused to swing back and forth from side to side, cutting out of the face of the drift a swath as wide as the depth of the rotary element. If the drift be high, the boom may first be swung up so as to make a cut across the top, and then it is lowered so as to clear away the lower snow. During this time the entire energy of the power plant of the power driven vehicle may be utilized solely for the purpose of operating the snow collecting or removing means, so that there is no danger of stalling the machine. After the snow has been removed from the roadway and banked at the sides, the boom may be swung around until it stands crosswise of the road. Then, when the machine is run along the road, the rotary remover will cut down the bank on one side and scatter the snow so as to prevent it from drifting back upon the roadway. The machine may then be operated in a direction to cause the bank on the other side to be cut down. At all times, the discharge outlet of the hood or housing associated with the rotary collector may be pointed in such a direction that the snow discharge therefrom will be travelling with the wind and will therefore be broadcast more or less instead of being piled up directly beside the road.

By providing the machine with a simple conveyor attachment, the snow that is collected may be deposited upon a conveyor and carried to trucks or other vehicles driven alongside the machine. Such an arrangement is shown in Figs. 12 and 13, in which there is an endless conveyor 92 mounted on suitable stationary supports 93 above the housing 32 and the arm 74 and suitably driven as, for example by a sprocket chain 94 passing around a sprocket wheel on the main shaft 28. The conveyor extends transversely of the machine so that it will discharge at one side of the machine snow deposited on the same. Associated with the conveyor is a shield or baffle 95 extending upwardly and forwardly from the vicinity of the edge farthest from the discharge spout. By pointing the spout so that it will be directed toward the baffle, snow that is collected will be forcibly driven against the baffle and from there will drop down upon the conveyor. In driving the snow against the baffle it is compacted and therefore, when discharged by the conveyor into a truck or the like it is no longer in the form of fluffy snow but consists of a comparatively dense mass. A machine of this kind is useful on city streets,

either to collect the snow in vehicles as it is being removed from any portion of the street, or to clean up banks of snow that have been formed by plows or other means. If the machine is not intended to do any of the work that can be done by ordinary plows, the V plow may be omitted and only the boom with its remover or collector employed.

I have not attempted to explain all of the uses of my improved machine or of its various features used individually or collectively, as there are many uses that are self-evident or that will occur to anyone having a full understanding of the machine. Therefore, while I have illustrated and described only a single preferred form of machine embodying all of the various features of my invention, and have explained only a few uses, I do not desire to be limited by this particular description and explanation; but intend to cover all forms and arrangements, used in whatsoever way, coming within the definitions of my invention constituting the appended claims; and I desire to have it understood that the word "vehicle" is used in the claims to indicate anything that may be moved along and, in some instances, might be a V-type or other plow.

I claim:

1. The combination with a snow plow, of a rotary snow remover narrower than the plow mounted to project in advance of the latter to form a narrow path in the snow in advance of the plow, and means for rotating said remover.

2. The combination with a snow plow, of a rotary snow remover narrower than the plow mounted to project in advance of the latter to form a narrow path in the snow in advance of the plow, means for rotating the remover, and means for shifting said remover bodily into an idle position.

3. The combination with a vehicle, of a boom projecting from the vehicle and mounted so as to be capable of swinging, and a rotary snow remover mounted on the outer end of the boom with its axis of rotation lying transversely of the boom, said remover comprising radial trough-shaped buckets having snow receiving inlets on both sides of the boom, and a deflector lying near the periphery of the remover to determine the direction of flow of the snow as it leaves the remover.

4. The combination with a vehicle, of a boom projecting from the vehicle and mounted so as to be capable of swinging vertically and horizontally, a rotary snow removing device mounted on the outer end of the boom, and means associated with the snow remover for causing the snow discharged from the latter to travel in any desired direction relatively to the axis of rotation of the remover.

5. The combination with a vehicle, of a boom projecting from the vehicle and mount-

ed so as to be capable of swinging vertically and horizontally, a rotary snow remover device mounted on the outer end of the boom, said remover having snow receiving inlets on sides and the end of the boom, and means associated with the snow remover for directing the flow of snow discharged from the latter.

6. The combination with a vehicle, of a remover mounted to project beyond the same and comprising a wheel having trough-shaped radial snow separating elements and means at the periphery of the wheel for receiving the snow discharged from the wheel, means for rotating the wheel, and means for moving the remover bodily relatively to and transversely of the vehicle.

7. The combination with a vehicle, of a remover mounted to project beyond the same and comprising a wheel having trough-shaped radial snow separating elements and means for receiving the snow discharged at the periphery of the wheel, means for rotating the wheel, and means for automatically moving the remover back and forth across the vehicle.

8. In combination, a vehicle, a swinging boom mounted on the vehicle and projecting beyond the same, a snow remover on the outer end of the boom, a conveyor on the vehicle, adjacent to the pivotal axis of the boom, and a discharge conduit for snow extending from the remover to the conveyor and terminating near said axis.

9. The combination with a vehicle, of a boom mounted on the vehicle so as to project therefrom, a rotary wheel mounted on the outer end of said boom so as to revolve about an axis transverse to the boom, said wheel comprising radial trough-shaped buckets, and means for rotating said wheel.

10. In combination, a vehicle, a swinging boom mounted on the vehicle and projecting beyond the same, a snow remover on the outer end of the boom, a conveyor on the vehicle adjacent to the pivotal axis of the boom, and means extending from the remover to a point near the conveyor for guiding snow from the remover to the conveyor.

11. The combination with a vehicle, of a boom projecting from the vehicle and mounted so as to be capable of swinging, a rotary snow collector at the outer end of the boom having snow inlets on both sides of and at the end of the boom and adapted to discharge the snow tangentially, means for rapidly revolving said collector, and means for controlling the direction of flow of the snow discharged by the collector.

12. The combination with a snow plow, of rotary means for collecting snow and discharging it at a high velocity, means associated with the collector to control the direction in which the discharged stream of snow flows and remove it from the path of the

plow, and means for moving collector and controlling means across the front of said snow plow.

13. The combination with a snow plow, of rotary means for collecting snow and discharging it at a high velocity, means associated with the collector to control the direction in which the discharged stream of snow flows, and means for moving collector and controlling means across the front of said snow plow from one side of the plow to the other and from a position near the ground to an idle position high above the ground.

14. The combination with a snow plow, of a boom, a rotary snow collector at one end of the boom, means for pivotally supporting the other end of the boom, the length of the boom and the position of the pivotal support being such that the boom may be swung to position the collector in front of the plow or at either side of the plow, means for rotating the said collector, and means associated with the collector for causing the snow entering the latter to be removed from the path of the plow.

15. The combination with a vehicle, of a boom mounted on the vehicle so as to project therefrom and be capable of swinging up and down and sidewise, rotary means at the outer end of said boom for collecting snow and discharging it by centrifugal force, and a deflector mounted on the boom adjacent to the periphery of said rotary means in position to guide the stream of snow discharged by said means.

16. The combination with a vehicle, of a boom mounted on the vehicle so as to project therefrom and be capable of swinging up and down and sidewise, rotary means at the outer end of said boom for collecting snow and discharging it by centrifugal force, and a deflector mounted on the boom adjacent to the periphery of said rotary means in position to guide the stream of snow discharged by said means, the outer part of the deflector being movable with respect to the boom thereby to permit the direction of the stream of discharged snow to be varied.

17. The combination with a vehicle, of a boom mounted on the vehicle so as to project therefrom, the outer end of the boom being in the form of two long separated parallel beams, a rotatable shaft extending transversely of the boom at the outer end, a series of radial trough-shaped buckets fixed to said shaft and rotatable in the space between said beams and means for rotating said shaft.

18. The combination with a vehicle, of a remover mounted to project beyond the same and comprising a wheel having trough-shaped radial snow separating elements and means at the periphery of the wheel for receiving the snow discharged from the wheel, means for rotating the wheel, and means for moving the remover bodily transversely of

the vehicle, and also in the vertical direction.

19. The combination with a vehicle, of a member mounted so as to be capable of swinging laterally thereon and projected therefrom, a wheel at the outer end of said member for collecting snow and compacting the same, a deflector mounted adjacent to the periphery of the wheel in position to guide the snow discharged by the wheel, and means for driving said wheel.

20. The combination with a vehicle, of a member projecting from the vehicle and mounted so as to be capable of swinging laterally and in the vertical direction, means at the outer end of said member for collecting snow and discharging it by centrifugal force, and means associated with the aforesaid collecting means to control the direction in which the snow is discharged therefrom.

In testimony whereof, I sign this specification.

ARTHUR B. WEBB.
